Filed Dec. 19, 1961, Ser. No. 67,984

Term of patent 14 years

(Cl. D71—1)

FIG. 4

FIG. 5

FIG. 1 is a side elevational view of a rotary-winged aircraft showing our new design;

FIG. 2 is a front elevational view thereof;

FIG. 3 is a top plan view thereof;

FIG. 4 is a front perspective view thereof; and

FIG. 5 is a rear perspective view taken from the side opposite that shown in FIG. 4.

The rotor blades are fragmentarily shown for convenience of illustration.

The dominant features of the design reside in the portions shown in full line.

We claim:

The ornamental design for a rotary-winged aircraft, substantially as shown and described.
